UNITED STATES PATENT OFFICE.

WILLIAM ANDERSON, OF HEBBURN-ON-TYNE, AND HENRY WILLIAM CLOTHIER, OF WALLSEND-ON-TYNE, ENGLAND, ASSIGNEES TO A. REYROLLE & COMPANY LIMITED, OF HEBBURN-ON-TYNE, ENGLAND, A COMPANY OF GREAT BRITAIN.

CONTROL MECHANISM FOR ELECTRIC SWITCH GEAR.

Application filed January 4, 1926, Serial No. 79,242, and in Great Britain January 14, 1925.

This invention relates to the control mechanism of electric switchgear of the kind in which the opening of the switch is effected by trip mechanism whilst the closing of the switch is brought about by the movement of a lever or handle.

Various constructions of switchgear of this type have been proposed and the operative connection between the handle and the arm 10 or lever operating the switch has been controlled by trip mechanism. In some forms the operative connection has been in the form of a toggle broken by the trip mechanism when some form of catch has been released.

Difficulty has been experienced in designing the gear so that the trip mechanism can operate during the whole of the closing movement of the switch and in many instances further difficulty has been experienced owing to 20 the wear on the catch materially altering the power necessary to operate the trip.

The primary object of the present invention is to obviate these disadvantages.

In switch-control mechanism according to 25 this invention the handle and the switch-operating arm or lever are arranged to turn about the same axis and the operative connection between them comprises a toggle so arranged that after being broken to open the 30 switch it is reset by the movement of the handle before that member can act to close the switch. Further, the toggle after being thus reset can be broken again by the trip mechanism at any stage in the closing movement of the switch. As soon as the actual closing 35 movement of the handle and switch lever is started, energy is stored which is available for the breaking of the toggle.

The trip mechanism itself preferably comprises a second toggle and a catch, these members being so arranged that substantially the same power is required to operate the trip whether the switch be closed or in the process of being closed. Moreover such power is 45 practically unaffected by wear of the catch.

The invention may be carried out in various ways but one construction is illustrated by way of example in the accompanying drawings, in which

50 Figure 1 is a sectional elevation of switch-control mechanism according to the invention

showing the various parts in their normal position when the switch is closed.

Figure 2 is a plan projected from the elevation shown in Figure 1, some of the details being omitted to avoid confusion.

Figure 3 is a view similar to that shown in Figure 1 showing the momentary position of the mechanism just as the toggle is breaking, but before the switch has actually opened.

Figure 4 is a view similar to that shown in Figure 3 showing the position of the mechanism after the switch has been tripped open but before the tripping mechanism has been reset and

65 Figure 5, also a view like that shown in Figure 3, shows the position of the mechanism when the switch is open and the handle is raised preparatory to closing the switch after having reset the tripping mechanism.

In the construction illustrated in the drawings the operating handle A is pivoted upon a spindle B supported in bearings in the switch-gear housing C and secured to this spindle B is a forked lever D which is attached to the 75 moving part of the switch (not shown) by means of ropes E. These ropes E are attached by means of eyelets E¹ to a bar E² carried in a slot in the lever D and are normally in tension owing to the tendency of the so switch to open.

On a spindle F carried by the lever D is pivoted one end of what may be referred to as the main toggle, which comprises two levers G¹ and G², whose adjacent ends are connected 85 by a pivot G³. The opposite end of the lever G¹ is pivoted to the lever D by means of the spindle F as stated above whilst the opposite end of the lever G² is pivoted at G⁴ to the shorter end of a forked lever H rotatably 90 mounted at H¹ on the upper part A¹ of the handle A. The toggle levers G¹ and G² are provided with a stop G⁵ which prevents relative movement of the two levers after they have passed the dead centre position by more 95 than a predetermined amount when moving towards the left in Figure 1.

The longer arm of the forked lever H is connected at H² by means of a link J to the shorter arm K¹ of a lever pivoted about the 100 same spindle B as the handle A. The longer arm K² of this lever, which may be termed

the catch lever, is provided with a roller K³ which engages with a catch L adapted to be released when it is required to trip the switch. This catch L is pivoted on a member M secured to a spindle M¹ carried in the switch-gear housing C. This member M is adapted to be moved by the action of the tappet N (Figure 2) secured to the spindle M¹, this tappet being actuated by electrical, mechanical or other means. Together with the catch L the pivoted member M forms a toggle so arranged that when the member M has been moved by a small amount the catch L rotates about its pivot and falls clear of the longer arm K² of the catch lever, thus releasing it. In this way the effect of wear of the catch surface on the action of the tripping mechanism is avoided.

The switch handle is made in two parts A² and A¹ connected by a pivot A² and having a spring A³ between them. The upper part A¹, which itself turns about the spindle B to which is secured the switch-actuating lever D, is locked when the switch is closed by a catch A⁴ which is released on the opening of the switch by a pin B¹ mounted on the spindle B. To trip the switch by hand the lower part A of the handle, which may be called the handle proper, is moved in the upward direction (i. e. towards the right in Figure 1), the compression of the spring A³ allowing relative motion between it and the locked upper part A¹. A projection A⁵ on the lower part A engages with the member M thereby releasing the trip catch L and operating the mechanism.

The action of the mechanism, whether tripped mechanically or by hand is as follows:—

Normally when the switch is closed the various parts are in the position shown in Figure 1, but on the release of the catch L the tension in the rope E pulls on the switch actuating lever D and causes it to rotate. The toggle G¹, G² is carried with the lever D and causes the lever H also to rotate about its pivot H¹, bringing the longer arm K² of the catch lever into the position shown in Figure 3.

As the lever H rotates, a projection H³ formed thereon comes into contact with the lever G² of the main toggle and pushes the toggle over its dead centre position, thus breaking it. As soon as the lever H has turned sufficiently to break the toggle, its further movement is prevented by a stop A⁶ on the upper part A¹ of the handle, which engages with the projection H³. The parts of the mechanism are now in the momentary position indicated in Figure 3 where the projection H³ is shown up against the stop A⁶ and the toggle is shown in the act of breaking.

As soon as the toggle has been broken the rigid connection between the switch-actuat-

ing lever D and the handle A is destroyed and the switch at once opens, the ropes E pulling the lever D and with it the main toggle G¹, G² into the position shown in Figure 4. The spindle B rotates with the lever D and as it does so the pin B¹ releases the catch A⁴ thereby freeing the handle and enabling it to be raised to reset the trip mechanism. Figure 4 shows the final position of the various parts when the switch is open, but before the mechanism has been reset.

To reset the mechanism the handle is raised as a whole into the position shown in Figure 5. This pulls on the main toggle G¹, G² and causes the lever H to rotate and the longer arm K² of the catch lever to engage with the catch L, the main toggle G¹, G² falling into position over dead centre by gravity. Lowering the handle again closes the switch, but as the trip mechanism must of necessity be reset by first raising the handle it is always ready for operation, even during the closing of the switch.

It will be appreciated that the application of the toggle principle to the catch L eliminates the effect of wear of the catch and ensures reliable operation of the trip mechanism. Further, its application to the catch lever K¹, K² and link J results in the load on the catch being kept as constant as possible throughout the operation of closing the switch.

What we claim as our invention and desire to secure by Letters Patent is:—

1. In control mechanism for an electric switch the combination of a pivoted handle, a switch-operating arm turning about the same axis as the handle, a forked lever pivoted on the upper part of the handle, a toggle normally over-set connecting the forked lever to the switch-operating arm and adapted to be broken by rotation of the forked lever about its pivot and means for preventing such rotation of the forked lever until the mechanism is tripped.

2. In control mechanism for an electric switch the combination of a pivoted handle, a switch-operating arm turning about the same axis as the handle, a forked lever pivoted on the upper part of the handle, a toggle connecting the forked lever to the switch-operating arm and adapted to be broken by rotation of the forked lever about its pivot, means for preventing such rotation until the mechanism is tripped, means for preventing further rotation of the forked lever after the toggle has been broken and a locking device for the handle so constructed that the handle is capable of limited movement in order to trip the switch but cannot be moved beyond this limit until the opening of the switch has released the locking device.

3. In control mechanism for an electric switch the combination of a pivoted handle, a switch-operating arm turning about the same

- axis as the handle, a forked lever pivoted on the upper part of the handle, a toggle connecting the forked lever to the switch-operating arm, a projection on the forked lever adapted to break the toggle, means for preventing further rotation of the forked lever after the toggle has been broken, a second toggle operatively connected to the forked lever, a catch for holding the second toggle against movement and a locking device for the handle so constructed that the handle is capable of limited movement in order to release the catch but cannot be moved beyond this limit until the opening of the switch has released the locking device.
4. In control mechanism for an electric switch the combination of a switchgear housing, a handle pivoted thereon, a switch-operating arm turning about the same axis as the handle, a forked lever pivoted on the upper part of the handle, a toggle connecting the forked lever to the switch-operating arm, a projection on the forked lever adapted to break the toggle, means for preventing further rotation of the forked lever after the toggle has been broken, a catch lever also turning about the same axis as the handle, a link forming a toggle with the catch lever and connecting the catch lever to the forked lever, a pivoted catch engaging with the catch lever when the trip mechanism is set and a locking device for the handle so constructed that the handle is capable of limited movement in order to release the catch but cannot be moved beyond this limit until the opening of the switch has released the locking device.
5. In control mechanism for an electric switch the combination of a switchgear housing, a handle pivoted thereon, a switch-operating arm turning about the same axis as the handle, a forked lever pivoted on the upper part of the handle, a toggle connecting the forked lever to the switch-operating arm, a projection on the forked lever adapted to break the toggle, means for preventing further rotation of the forked lever after the toggle has been broken, a second toggle operatively connected to the forked lever, a member pivoted to the switchgear housing, a catch for holding the second toggle from movement pivoted to this member and forming a third toggle therewith and means for releasing the catch.
6. In control mechanism for an electric switch the combination of a switchgear housing, a handle comprising an upper part pivoted to the housing and a lower part yieldingly connected to the upper part by means of a pivot and a spring, a switch-operating arm turning about the same axis as the handle, a forked lever pivoted on the upper part of the handle, a toggle connecting the forked lever to the switch-operating arm and adapted to be broken by rotation of the forked lever about its pivot, means for preventing such rotation until the mechanism is tripped, a projection on the lower part of the handle adapted to release the trip mechanism and a locking device for the handle so constructed that the lower part of the handle with its projection is capable of limited movement in order to trip the switch whilst the upper part is held stationary until the opening of the switch has released the locking device.
7. In control mechanism for an electric switch the combination of a switchgear housing, a handle comprising an upper part pivoted to the housing and a lower part yieldingly connected to the upper part by means of a pivot and a spring, a switch-operating arm turning about the same axis as the handle, a forked lever pivoted on the upper part of the handle, a toggle connecting the forked lever to the switch-operating arm, a projection on the forked lever adapted to break the toggle, a stop on the upper part of the handle adapted to prevent further rotation of the forked lever after the toggle has been broken, a second toggle operatively connected to the forked lever, a catch for holding the second toggle against movement and a locking device for the handle so constructed that the lower part of the handle is capable of limited movement in order to release the catch, whilst the upper part is held stationary until the opening of the switch has released the locking device.
8. In control mechanism for an electric switch the combination of a switchgear housing, a handle comprising an upper part pivoted to the housing and a lower part yieldingly connected to the upper part by means of a pivot and a spring, a switch-operating arm turning about the same axis as the handle, a forked lever pivoted on the upper part of the handle, a toggle connecting the forked lever to the switch-operating arm, a projection on the forked lever adapted to break the toggle, a stop on the upper part of the handle adapted to prevent further rotation of the forked lever after the toggle has been broken, a second toggle operatively connected to the forked lever, a member pivoted to the switchgear housing, a catch for the second toggle pivoted to this member and forming a third toggle therewith, a projection on the lower part of the handle adapted to release the catch and a locking device for the handle so constructed that the lower part of the handle with its projection is capable of limited movement in order to release the catch whilst the upper part is held stationary until the opening of the switch has released the locking device.
9. In control mechanism for an electric switch the combination of a switchgear housing, a handle comprising an upper part pivoted to the housing and a lower part yieldingly connected to the upper part by means of a pivot and a spring, a switch-operating arm

arm turning about the same axis as the handle, a forked lever pivoted on the upper part of the handle, a toggle connecting the forked lever to the switch-operating arm, a projection on the forked lever adapted to break the toggle, a stop on the upper part of the handle adapted to prevent further rotation of the forked lever after the toggle has been broken, a catch lever also turning about the same axis as the handle, a link forming a toggle with the catch lever and connecting the catch lever to the forked lever, a member pivoted on the switchgear housing, a catch pivoted on this member and forming a toggle

therewith and adapted to engage the catch lever when the trip mechanism is set, a projection on the lower part of the handle adapted to release the catch and a locking device for the handle so constructed that the lower part of the handle with its projection is capable of limited movement in order to release the catch whilst the upper part is held against movement until the opening of the switch has released the locking device. 15

In testimony whereof we have signed our names to this specification.

WILLIAM ANDERSON.

HENRY WILLIAM CLOTHIER.
